United States Patent Office

Des. 221,846
Patented Sept. 14, 1971

221,846

ENVIRONMENTAL WORK STATION

Warren E. Dexter, Fairfax, Va.
(P.O. Box 395, Annandale, Va. 22003)

Filed Apr. 1, 1970, Ser. No. 22,168

Term of patent 14 years

Int. Cl. D24—01
U.S. Cl. D16—2

FIG. 1 is a perspective view of the environmental work station embodying my design;

FIG. 2 is a top plan view thereof;

FIG. 3 is a rear elevational view thereof;

FIG. 4 is a side elevational view thereof.

I claim:

The ornamental design for an environmental work station, substantially as shown.
